UNITED STATES PATENT OFFICE.

A'QUILLA DUENSING, OF ALTOONA, IOWA.

PRINTING DEVICE.

1,353,032.

Specification of Letters Patent. Patented Sept. 14, 1920.

Application filed May 8, 1919. Serial No. 295,731.

To all whom it may concern:

Be it known that I, A'QUILLA DUENSING, a citizen of the United States, and resident of Altoona, in the county of Polk and State 5 of Iowa, have invented a certain new and useful Printing Device, of which the following is a specification.

The object of my invention is to provide a machine of simple, durable and inexpensive construction adapted to print a series 10 of names or addresses or the like on paper during the movement of the paper, so that such names or addresses may be printed without stopping the movement of the paper, whereby there is effected a substantial 15 saving of time and a substantial reduction of the wear on the printing machine.

More particularly it is my invention to provide a machine of the type under consideration in which address carrying plates or the like are successively moved to printing position, and are held in printing position during the movement of the parts, so that the paper can be printed during its 25 movement.

Still a further object is to provide such a device having means, whereby it may be thrown into and out of gear, such means being so arranged that when the device is 30 thrown into gear it will always operate to bring the printing plates to printing position at the proper time in the operation of the machine.

A further object is to provide such a device including a base from which paper may 35 travel, or on which paper may be placed for printing, which device includes mechanism for successively presenting address plates to printing position with relation to the paper, said mechanism being adjustable laterally with relation to the plates, so that the matter from the plates may be printed 40 at different positions with relation to the position of the paper.

With these and other objects in view my 45 invention consists in the construction, arrangement and combination of the various parts of the device, whereby the objects contemplated are attained, as hereinafter more 50 fully set forth, pointed out in my claims and illustrated in the accompanying drawings, in which:

Figure 1 shows a side elevation of an

address printing device embodying my invention.

55

Fig. 2 shows a top or plan view of the same illustrated on a printing press.

Fig. 3 shows a detail view of part of the mechanism.

Fig. 4 shows a sectional view through the clutch device.

Fig. 5 shows a vertical, sectional view through the address printing mechanism, taken on the line 5—5 of Fig. 1.

Fig. 6 shows a detail, sectional view taken 65 on the line 6—6 of Fig. 5.

Fig. 7 shows a detail, sectional view taken on the line 7—7 of Fig. 5;

Fig. 8 shows a detail, sectional view of a portion of the mechanism for causing the 70 swinging movement of the address plate carrying frame.

Fig. 9 shows a side elevation of a form of my device supported on its own frame and independent of any printing press or 75 the like; and

Fig. 10 shows a longitudinal, sectional view through the device shown in Fig. 9.

My improved device may be used as an independent mechanism employed with any 80 means for feeding stock to be printed to printing position with relation to the address carrying plates, or may be used as illustrated herein in connection with a printing press.

85

In the accompanying drawings I have shown my device installed on a printing press having the frame 10. The printing press frame has transverse shafts 12 and 13 clearly shown in Fig. 2, and also has 90 the bed 14 shown in Fig. 1.

It will be understood that I have not attempted to accurately illustrate any particular form of printing press, but rather to illustrating supporting frame members of 95 the kind which may represent a printing press or may represent a part of my device when used as an independent mechanism.

A strip of paper, printed or otherwise is extended around guide rollers 17 and 16 100 and along the bed 14 to any suitable point.

My improved address printing device comprises a pair of laterally spaced, longitudinal frame members 18. Connected with each frame member 18 is a suitable frame 19 105 which may be cast or otherwise constructed

and is adapted to support the various shafts and other parts of the machine.

5 Mounted in suitable bearings 20 on the frame members 18 is the main power shaft 21 of the machine.

The frame members 18 may be supported on any suitable frame or support, and, as shown in the form of the invention illustrated herein, said frame members are provided at their opposite ends with bearings 22 through which the shafts 12 and 13 are extended.

10 The operative parts of my device supported by the frame members 18 are adjustable on the shafts 12 and 13 and may be locked in any adjusted position by means of the set screws 23.

15 Fixed on the shaft 21 are spaced cams 24. Supported on the shaft 21 in the manner hereinafter described, is a supporting frame comprising the laterally spaced, normally upright members 25, preferably connected by a cross member 26. At the upper ends of the members 25 are casings 27 arranged adjacent to the opposite outer surfaces of the cams 24, and extending over the tops of said cams, as illustrated in Fig. 5, preferably having at their inner adjacent upper edges downwardly extending flanges 28 and forming journals for said cams.

20 In the walls of the casings 27 are holes 29 to receive the shaft 21, which holes are of considerably greater diameter than the shaft 21 to permit raising and lowering of the casings and the frame members 25 when the shaft is rotated, for bringing different parts of the cams 24 uppermost.

25 In the lower ends of the frame members 25 are vertically slidable bearings 30.

30 On the lower ends of the frame members 25 are plates 31 which are removable for removing the vertically slidable bearings 30. The bearings 30 slide in suitable guide-ways in the frame members 25 and are yieldably held at the downward limits of their movement by means of a spring 33.

35 Detachably mounted in the bearings 30 is a transverse shaft 34 on which is a roller 35 having a plurality of flat sides, which roller is preferably octagonal in cross section.

40 At the upper end of each frame member 25 is a frame member 36. Mounted on the frame members 36 is a transverse shaft 37 on which is a roller 38.

45 Spaced longitudinally in the machine from the shaft 37 is another transverse shaft 39 on which is a roller 40 having near its ends peripheral rows of teeth or pins 41.

50 Mounted in the frame members 36 in vertically arranged guide-ways 42 are vertically slidable bearings 43. Above the bearings 43 are plates 44.

55 Springs 45, arranged between the plates 44 and the slidable bearings 43, tend to hold

said slidable bearings at the lowermost positions of their movement.

60 Mounted in the bearings 43 is a transverse shaft 46 on which is mounted a roller 47, having at its ends annular grooves 48 arranged to register with the respective rows of pins 41.

65 On the roller 47 between the grooves 48, I preferably provide a cushioning cover 50 of felt or rubber or other suitable material.

70 Fixed on one end of the shaft 39 is a ratchet wheel 51.

75 Pivoted on the shaft 46 is a pawl 52 arranged to coact with the ratchet wheel 51 to prevent movement thereof in one direction.

80 Pivoted on the frame of the machine is a pawl 53 having a hook member 54 arranged to be yieldingly held in engagement with the teeth of the ratchet wheel 51 by means of a spring 55.

85 Suitably mounted on the frame of the machine and spaced laterally from the shaft 21 is a stub shaft 56, on which is a gear 57 in mesh with a gear 58 on the shaft 21.

90 Suitably mounted on the machine is a shaft 59 on which is a gear 60 which meshes with the gear 57.

95 Pivoted to the frame portion 36 is an arm 61 slidably extended over a guide support 62 to position adjacent to the shaft 59, having on its upper edge teeth 63 preferably arranged substantially below said shaft 59.

100 On the shaft 59 is mounted a segmental gear 64 arranged to coact with the teeth on the arm 61. The arm 61 really forms a rack bar with a limited number of teeth.

105 Secured to the frame portion 36 and to some support, such, for instance, as the fixed frame 10 is a spring 65 which serves to cushion the movement of the swinging frame members 25.

110 Located near the lower part of my device is an inking roller 66 which is operated from a chain of gears 57, 68, 69 and 70 from the gear 60 on the shaft 59.

115 Suitably supported are rollers 71 and 72 preferably above and at opposite ends of my device.

120 Mounted on the roller 71 are address plates 73 suitably connected and linked together by chains 74.

125 The address plates 73 are provided near their ends with holes 75, so arranged as to coact with the pins 41 on the roller 40.

130 The chains 74 and address plates are threaded over the roller 38 and between said roller and the roller 47, thence downwardly around the flat sided roller 35, thence upwardly between the rollers 40 and 47 and then they are wound on the roller 72.

The plates 73 are provided near their ends with holes 75 which receive the pins 41, so that when the shaft 39 and roller 40 are rotated the pins 41 will advance the plates 73.

Mounted on the shaft 21 is a disk 76 forming a clutch member, and held by means of a journal 77 against lateral sliding movement with relation to the frame 10.

5 The disk 76 is non-rotatably mounted on the shaft 21 by means of a key 78, fixed to said disk and traveling in a long slot 78^a in the shaft 21.

On the face of the disk 76 are diametrically opposite pins 80 and 81. The pin 81 is considerably larger in diameter than the pin 80.

10 Mounted on the shaft 21 is a sleeve 79 having at one end an annular flange 82. Rotatably mounted on the sleeve 79 is another sleeve 83 having at one end a gear 84 and at the other end a disk 85 provided with holes 86 and 87 of different diameters, and adapted in one position of the disk 85 to register 15 with and receive the respective pins 80 and 81.

Secured to the end of the sleeve 79 opposite the flange 82 is a key 88 which projects into an annular rabbet 88^a in the 20 sleeve 83.

25 The sleeve 83 has a pair of spaced, annular ribs 88^b. Received between the ribs 88^b on opposite sides of the sleeve 83 are the arms of a bifurcated lever 88^c which is 30 pivoted on a bracket 88^d. It will be seen that the disk 76 and the pins thereon, and the disk 85 with the holes therein form clutch members, the latter being movable and controllable through the means of the 35 lever 88^c.

On the shaft 21 is mounted a tubular arm 90 in which is slidably mounted a plunger pin 91. The wall of the tubular arm 90 is provided with opposite longitudinally 40 elongated slots 92.

45 Mounted in the plunger pin 91 is a pin 93 which travels in the slots 92 and on one side of the arm 90 extends substantially beyond said arm.

Arranged in the path of travel of the projecting part of the pin 93 is a cam surface 94. On one of the casing members 27 is a laterally extending arm 95 which extends into the path of the plunger pin 91.

50 Arranged in the path of travel of the outer end of the plunger pin 91 is an inclined spring 96.

55 The arrangement and construction of the parts just described will be more fully set forth in connection with the description of the practical operation of my machine.

In the practical use of my improved address printing machine, when the paper 15 is being drawn through the machine the operation of my device is as follows:

60 In this connection it may be mentioned that my device may be independently used on the printing press when desired and may be operated by means of a crank 88^f on the 65 shaft 21, or in any suitable way, or my de-

vice may be arranged to operate from some moving part of the printing press through the medium of a wide gear 88^e meshing with the gear 84.

Assume that the sleeve 83 is rotated, then 70 when the holes 86 and 87 are moved toward the pins 80 and 81, it will be noted that when the pin 81 registers with the hole 87, when the handle of the lever 88^c is being pressed away from the machine, the pins 80 and 81 75 will enter the holes 86 and 87 whereupon rotation will be imparted to the shaft 21.

As the shaft 21 is rotated the arm 90 moves to position where the outer end of the plunger pin 91 engages the arm 95 as illustrated in Figs. 5 and 6. As the travel of the arm 90 continues, the engagement of the plunger pin 91 with the arm 95 will swing the lower end of the swinging frame members 25 to position where one of the plates 80 73 engages the inking roller 66 for inking the type or address carrying means on the plate 73.

Just as the parts reach the position last mentioned the pin 93 reaches the highest 90 point of the cam 94 and slides over the end of said cam.

As the arm 95 slides over the spring 96 such spring will be depressed, as illustrated 95 in Fig. 6 in full lines.

Just before the pin 93 clears the highest point of the cam 94, the arm 95 passes and clears the spring 96, whereupon the spring 96 will spring upwardly to its position 100 shown by dotted lines in Fig. 6.

The spring 96 has a downwardly extending end 96^a which then stands in the way of the return movement of the arm 95.

After the address plate 73 has been inked, 105 gravity will tend to return the arms 25 to their vertical position, but as soon as the address plate moves over the inking roller, the arm 95 engages the portion 96^a of the spring 96, whereby any further return of the frame members 25 toward vertical position is automatically prevented.

The further rotation of the shaft 21 brings the cams 24 to such position as to raise the frame members 25 and parts supported thereon with relation to the shaft 21, for thereby raising the arm 95 to position to clear the spring 96 and permit the return of the frame members 25 toward their opposite position.

The parts of the machine are so arranged 120 that at this point in the operation thereof, the teeth of the segmental gear 64 engage the teeth on the arm 61 for pulling the arm 61 toward the left, as shown in Fig. 8, thereby swinging the roller 35 downwardly and 125 past center.

The spring 65 holds the parts in their last described position until the shaft 21 is rotated to position for again bringing the plunger pin 91 into engagement with the 130

arm 95, whereby the roller 35 is again swung toward the inking roller.

As the roller 35 passes center, the cams 24 are in such position that the roller 35 is 5 in its lowermost position, and as the roller 35 swings past center the printing operation is performed on the paper 15 which travels toward the right as in Fig. 1.

It will thus be seen that the printing operation 10 is performed on the moving paper and without any interruption of the movement of the paper.

As the roller 35 swings toward the inking roller, the hook 54 on the pawl 53 slides over 15 one of the teeth of the ratchet wheel 51, and on the return movement of the roller 35 the engagement of the hook 54 with the ratchet wheel 51 imparts a rotary movement to the shaft 39, thereupon the pins 41 will impart 20 some movement to the plates 73.

The parts just described are so arranged that for each completed swing of the frame members 25, the chains 74 are advanced a proper distance to bring a new plate to 25 printing position on the roller 35.

It will be noted that whenever the machine is thrown out of gear, the arrangement of the clutch device is such that it can only be thrown into gear when the disk 76 is in a 30 certain position with relation to the disk 85, and thus when the gear 88^s is operated from some moving part of a printing press, the operation of my device will be timed properly with relation to the operation of 35 the printing press.

By this arrangement the parts may be so timed that the plates will always be in printing position during the proper swinging movement of the swinging frame.

40 It will be noted that by loosening the screws 23 it is possible to slide the operative parts of the mechanism laterally with relation to the frame and with relation to the path of travel of the paper, so as to print 45 the address or other subject matter from the plates 73 at different places with relation to the paper being printed, and this may be done without any interference with the gearing connection from the gear 84 and the 50 gear 88^s to the printing press where my device is used with such press.

From the foregoing description it will be obvious that I have provided a simple and inexpensive machine, whereby a series of 55 address plates are successively brought to printing position on the roller 35. The roller 35 is given a peculiar movement. For instance, from its position shown in Fig. 1, the roller 35 is first swung upwardly and 60 toward the left while being raised above the paper to be printed. The roller is then swung downwardly to the right and is also lowered so as to be in printing position during such swinging movement.

65 When the roller reaches the extreme left

point of its movement, one of the printing plates is inked, and thereafter the roller is held in raised position while it is swung toward the right so as not to interfere with the moving paper.

The address may be printed on newspapers or the like, and it will be seen that with my device paper can be printed from a roll with a continuous movement, and the printing of the addresses can be accomplished 75 without interfering with this continuous movement of the paper 15.

It will, of course, be obvious that where the paper 15 from a roll is not used envelopes or any other stock may be placed in 80 position to be printed in any suitable way, and the addresses may be placed in position to be printed in any suitable way and the addresses may be successively printed on the stock. For the latter purpose any suitable 85 means may be used for imparting rotation to the main operating shaft 21.

In Figs. 9 and 10 I have shown my device in which the parts are supported on the frame 200. The parts are the same as those already described with the exception that there is provided an endless belt 201 mounted on rollers 202 and 203 on shafts 204 and 205 supported on the frame.

On the shaft 204 is a gear 206 in mesh 95 with the gear 67 already described.

Below the upper stretch of the endless belt 201 is a support 208 for holding the belt and the stock thereon during the printing operation.

Adjacent to the frame 200 is a table or the like 209 having arms 210 pivoted on the shaft 205 and having a supporting leg 211.

The printing stock 212 may be moved from the table 209 on to the endless conveyer 105 and held in position by hand or otherwise for the printing operation.

When the form of the device shown in Figs. 9 and 10 is used, the crank 88^s may be provided for operating the machine, or the 110 machine may be operated by power or any suitable source of energy.

I realize that numerous changes may be made in the details of the construction and arrangement of the parts of my improved device, and it is not my intention to limit myself in my claims to the specific form shown in my drawings, but it is my intention to cover by said claims any modified forms of structure or use of mechanical 115 equivalents which may be reasonably included within their scope.

I claim as my invention:

1. In a machine of the class described; a fixed frame; a movable frame thereon; means for successively bringing printing devices to printing position with relation to said movable frame; and means for operating said frame for causing a printing operation from said printing devices while said 130

- printing devices are in movement; said means including mechanism for raising said movable frame and swinging it in one direction, and then lowering the movable frame and swinging it in another direction. 5
2. In a machine of the class described; a fixed frame; a movable frame thereon; means for successively bringing printing devices to printing position with relation to said movable frame; means for operating said frame for causing a printing operation from said printing devices while said printing devices are in movement, said means including mechanism for raising said movable frame and swinging it in one direction, and then lowering the movable frame and swinging it in another direction; and means for inking said printing devices in one position of said movable frame. 10
3. In a machine of the class described; a fixed frame having a printing base; a movable frame thereon; means for swinging said movable frame in one direction; means for swinging the movable frame in the opposite direction; means for raising and lowering said frame between the respective swinging movements; a series of devices designed to be used in printing; and means for successively moving said devices to printing position, and carrying them with said movable frame. 15
4. In a machine of the class described; a fixed frame having a printing base; a movable frame thereon; means for swinging said movable frame in one direction; means for swinging the movable frame in the opposite direction; means for raising and lowering said frame between the respective swinging movements; a series of devices 20 designed to be used in printing; means for successively moving said devices to printing position, and carrying them with said movable frame; said means being actuated by the swinging movement of said frame. 25
5. In a device of the class described; a fixed frame; a printing base; a movable frame mounted on said fixed frame; means for swinging said movable frame to and fro; means for raising and lowering said movable frame; a series of printing devices 30 flexibly connected together; a flat sided roller at the lower side of said frame; a plurality of rollers at the upper part of said frame; said printing devices being threaded between the rollers at the upper part of the frame and around said flat sided roller, whereby the printing devices between the upper roller and the flat sided roller are held substantially taut. 35
6. In a device of the class described; a fixed frame; a base; a movable frame; a flat sided roller at the lower part of said movable frame; a series of printing devices flexibly connected extending around said roller; gripping rollers at the upper part 40 of said frame adapted to engage the stretches of said flexibly connected printing devices on opposite sides of said flat sided roller; means for alternately swinging said movable frame in a different direction, and for raising and lowering said movable frame; a gearing device; means for operatively connecting said gearing device with said movable frame; said means including a clutch device adapted to be engaged when said gearing device is in certain of its positions with relation to the movable frame. 45
7. In a device of the class described; a fixed frame; a base; a movable frame; a flat sided roller at the lower part of said movable frame; a series of printing devices flexibly connected extending around said roller; gripping rollers at the upper part of said frame adapted to engage the stretches of said flexibly connected printing devices on opposite sides of said flat sided roller; means for alternately swinging said movable frame in a different direction, and for raising and lowering said movable frame; engaging devices on one of said rollers adapted to engage and coat with said printing devices; a ratchet on said last named roller; and a pawl adapted to coat with said ratchet for intermittently imparting rotation to said last named roller. 50
8. In a device of the class described; a fixed frame; a shaft mounted on said fixed frame; and adapted to slide laterally thereon; cams on said shaft; a movable frame pivotally supported on said cams, so that by the rotation of the shaft and the operation of the cams, the movable frame is alternately raised and lowered; a flat surfaced roller at the lower end of said frame; a plurality of printing devices flexibly connected together and extended around the flat surfaced roller; a plurality of rollers at the upper portion of said movable frame, for engaging and gripping the stretches of said printing devices on opposite sides of said flat surfaced roller; and means for alternately swinging said movable frame to and fro. 55
9. In a device of the class described; a fixed frame; a shaft mounted on said fixed frame, and adapted to slide laterally thereon; cams on said shaft; a movable frame pivotally supported on said cams, so that by the rotation of the shaft and the operation of the cams, the movable frame is alternately raised and lowered; a flat surfaced roller at the lower end of said frame; a plurality of printing devices flexibly connected together and extended around the flat surfaced roller; a plurality of rollers at the upper portion of said movable frame, for engaging and gripping the stretches of said printing devices on opposite sides of said flat surfaced roller; means for alternately swinging said movable frame to and fro; 60

- said means comprising an arm on said shaft; a member slidably mounted in said arm, and yieldably held at its outer limit of movement; a projecting device on said member; a cam arranged in the path of said projecting device; an arm on said movable frame, arranged to stand in the path of said member; a spring arranged in the path of said arm, and adapted to be depressed by said arm, and to spring into the path of said arm, after the arm has cleared said spring; whereby said member engages the arm on said movable frame, the movable frame is swung to one limit of its movement, and is then held in said limit by said spring, until the removable frame is raised by the cams to clear said spring; and means for swinging the movable frame in the opposite direction.
- 10 10. In a device of the class described; a fixed frame; a shaft mounted on said fixed frame, and adapted to slide laterally thereon; cams on said shaft; a movable frame pivotally supported on said cams, so that by the rotation of the shaft and the operation of the cams, the movable frame is alternately raised and lowered; a flat surfaced roller at the lower end of said frame; a plurality of printing devices flexibly connected together and extended around the flat sur-

faced roller; a plurality of rollers at the upper portion of said movable frame, for engaging and gripping the stretches of said printing devices on opposite sides of said flat surfaced roller; means for alternately 35 swinging said movable frame to and fro; said means comprising an arm on said shaft; a member slidably mounted in said arm, and yieldably held at its outer limit of movement; a projecting device on said member; a cam arranged in the path of said projecting device; an arm on said movable frame, arranged to stand in the path of said member; a spring arranged in the path of said arm, and adapted to be depressed by said 40 arm, and to spring into the path of said arm after the arm has cleared said spring, whereby said member engages the arm on said movable frame, the movable frame is swung to one limit of its movement, and is then held in said limit by said spring, until the removable frame is raised by the cams to clear said spring; means for swinging the movable frame in the opposite direction; said last means comprising a shaft; a segmental gear thereon; a rack bar pivoted to said movable frame for coacting with said 45 segmental gear.

A'QUILLA DUENSING.
